TIMING MECHANISM

Harrison I. Turner, Cordova, Ill.

Application August 6, 1947, Serial No. 766,555

16 Claims. (Cl. 161—1)

1

My invention relates to timing switches and mechanisms and particularly to switches embodying means for accurately fixing a time interval within wide limits.

Timing switches constructed according to my invention are especially adapted to controlling the time cycle of operations of welding devices, motors, heaters, roasters, driers, and a large variety of machines, devices and processes which are equipped for control by the opening or closing of an electric circuit.

The objects of my invention are to furnish a timing switch capable of accurate and highly reliable performance with means for the quick and convenient setting and adjusting of time intervals; to furnish a timing switch which, when once its time interval has been set or adjusted, will automatically maintain its setting or adjustment without requiring resetting or the manual tightening of a screw or nut or of other locking means. Other objects will appear from the description.

Various types of timing switches designed to control industrial machinery have been available for years, but in those timers which have provided convenience of adjustment, accuracy, and flexibility approaching that of the invention disclosed herein, there has been employed as an essential part of the mechanism a nut arranged for travel along a screw, which combination, when exposed to dust and grit or even oil or grease of high viscosity, has often proved sluggish in operation or has failed entirely to operate when intended. In such timers, there has been no automatic means of locking the adjusting means so that repeated operations of the mechanism could not disturb the setting or adjustment. On the contrary, a clamping screw or nut has been required for that purpose, and has proved a source of serious trouble due to the frequent failure of an operator to tighten the screw or nut sufficiently or, in certain instances, due to the attempts of an operator to lock the adjustment securely by applying a wrench or pliers to the locking screw or nut and the consequent destruction of the locking mechanism.

My apparatus includes a housing in which the various parts are mounted; a motor with reduction gearing from the motor shaft to a clutch shaft; a clutch having one member rigidly united to the clutch shaft and a movable member carried by a sleeve mounted on the shaft; a driving sleeve rigidly united to the clutch shaft; a plurality of successively co-acting rings mounted upon the driving sleeve which may be referred to

2

as "primary" driving rings, and an additional series of successively co-acting rings which may be referred to as "secondary" driving rings mounted upon a second shaft; a terminal ring in the secondary series so arranged that when the secondary rings are completely gathered, it will cause the primary clutch shaft to revolve and cause the primary rings to start to gather; a trip-ring in the primary series arranged to trip a switch which may cut off the current to the motor or which may form a connection for the electric current to a solenoid that in turn will actuate other tripping means to reverse the movement of the machine in which the timer is mounted.

My apparatus also includes means by which the relative position or setting of both the primary and secondary rings may be adjusted at any desired point and a dial with hands to indicate the set position and the time required to complete the gathering operation of the rings so as to effectuate the tripping operation.

Various objects and advantages of this invention will be apparent upon consideration of the following detailed description of certain illustrative embodiments of the invention shown in the accompanying drawings, in which,

Figure 1 is a front elevation of my timer showing only portions of the contact mechanism and adjusting means;

Figure 2 is a sectional elevation of the timer taken substantially on the line 2—2 of Figure 4;

Figure 3 is a section of the timer taken on the line 3—3 of Figure 5, but omitting the adjusting dial mechanism shown in Figures 4 and 21;

Figure 27 is a top view of an assembly employed in applying the motion of the solenoid plunger to change the conditioning of timer contacts and of the clutch mechanism;

Figure 28 is a front view of the assembly shown in Figure 27;

Figure 29 is a detail of actuating arm 180;

Figure 30 is a diagram of the circuits of the timer when connected for operation in a typical one of the several ways in which the timer may be applied;

Figure 31 is a partial sectional detail view on line 2-2 of Figure 4 showing the position of the timer contacts and the various driving rings at an intermediate point while a typical timing cycle is in progress;

Figure 32 is a partial section detail view on line 4-4 of Figure 5 showing the position of various parts at the commencement of a typical timing cycle;

Figure 33 is a partial sectional detail on line 4-4 of Figure 5 showing the position of various parts at the end of a typical forward rotation of the driving ring assemblies;

Figure 34 is a detail of the link and the solenoid plunger connected thereto with pin 144 in the position it would occupy when the timer is so arranged that the plunger would be held down in the solenoid coil when the timer is at rest.

Similar numerals refer to similar parts throughout the several views.

In the following description, the term "right side" indicates the side to the right of a person facing the front or dial side of the timer.

The body or frame of the timer consists of a right side plate 1, a left side plate 2, a motor mounting plate 3 attached to side plate 2 by three mounting studs 4, a front plate 5 united to and which holds right and left side plates in proper spaced relation and supports the adjusting dial structure, and a back plate 6, which, like front plate 5, serves to keep the right and left side plates in proper spaced relation. Lips or flanges 7 extending from the side plates serve as a means whereby the back and front plates may be fastened to the side plates by screws 5.1 and 6.1, rivets or other suitable means.

The timing mechanism is driven by a small motor 8 which must rotate at an accurately controlled speed (as does a synchronous motor) to

provide the intended accuracy of operation. This motor is mounted upon the plate 3 and drives the main or clutch shaft 9 of the timer through a train comprising pinion 10, idler 11, clutch spur gear 13, sleeve 16 and clutch members 17 and 18. Pinion 10 is rigidly coupled to the output shaft of the motor. Idler 11 rotates about pivot-stud 12 extending from motor mounting plate 3 and drives gear 13 which is supported for rotation about and longitudinal movement along the exterior surface of sleeve or axle-bearing 14. Sleeve 16, to the right end of which gear 13 is rigidly united, slides on the main or clutch shaft 9. Clutch member 17 is rigidly installed on the left end of sleeve 16 and may engage clutch member 18 which is rigidly fastened to collar 19 which in turn is rigidly united to shaft 9 by a set screw or other suitable means. Inside of sleeve 16 a spring 20 and a collar 21, (see Figs. 7, 8 and 9) are installed so that spring 20 at its right end forces collar 21 against bearing 14. Axle-bearing 14 is rigidly held in place by press fit in mounting plate-bracket 3 (Fig. 2) and holds collar 21 (Fig. 7) against longitudinal movement to the right. The left end of spring 20 presses against inner face 22 of sleeve 16 and tends to urge clutch member 17 into engagement with clutch member 18. Collar 21, which is shown enlarged in Figures 8 and 9, is held against rotation with respect to sleeve 16 by set screw 23 which extends into slot 24, but collar 21 is not prevented from translation with respect to sleeve 16. The purpose of collar 21 is to form a thrust bearing in connection with sleeve-bearing 14. Accordingly, the right end of collar 21 is free to rotate against the left end of bearing 14 and yet is held against rotation with respect to sleeve 16.

The gripping surfaces of clutch members 17 and 18 may be notched like the teeth of a saw, so that when the two surfaces are engaged the teeth furnish a positive driving coupling between motor 8 and shaft 9. These teeth are so shaped that they provide their positive driving torque when the clutch member 17 is rotating in a counter-clockwise direction when viewed from the right side of the timer. The accuracy with which the time interval between the start of a cycle of operation of the timer and the end of the cycle agrees with the interval indicated on the timer dial, of which a description is herein-after provided, depends in large degree upon the number of the saw teeth in the periphery of the clutch surface. It has been found practical to divide a clutch surface of one and one quarter inch diameter into as many as one hundred teeth.

When clutch members 17 and 18 are to be disengaged as shown in Figures 2, 5, 7 and 12, the surfaces are separated by the action of clutch release lever 25 which is a bell crank lever pivoted at 25.1 in frame or bracket 26 and arranged for actuation by push rod or bar 27. The operation of separating the clutch faces against the force provided by spring 20 is accomplished by the pressure of arm of clutch release lever 25 against a shoulder of sleeve 16, as shown in Figure 12. When no force is exerted by push rod 27, the spring 20 forces the clutch faces into engagement. Push rod 27, which in one application of the timer, is connected to operating arm 28 by pin 29 (see Fig. 3), is pushed and pulled as needed for disengaging or engaging the clutch faces and acts by the partial rotation of shaft 31 carrying sleeve 30 united thereto by set screw 32, with operating arm 28 united to sleeve 30. Push rod 27

may be prevented from slipping off pin 29 by any common type of spring pin, which fits over the groove in pin 29.

It should be noted that, as the clutch faces approach or draw away from each other, gear 13 moves correspondingly and its teeth which engage the teeth of idler 11 (see Fig. 2), must slide back and forth lengthwise of the teeth of idler 11. Gear 13 is made thicker than idler 11 so that in its different positions substantially the entire length of the engaging teeth of idler 11 will be in contact with tooth surfaces of gear 13. It should also be noted that shaft 9 passes through and rotates within sleeve-bearing 14 which serves as the left support for shaft 9.

The right end of shaft 9 rotates in bearing 33 which is pressed into side plate 1. Rigidly fastened to shaft 9 by set screw 34 is sleeve 35 shown most clearly in Figure 13. Installed on shaft 9 and partly concealed from view by sleeve 35 is reset spring 36. It should be noted that shaft 9 is not of uniform diameter throughout, but is enlarged, as shown in Figure 13, in that portion which is encompassed by spring 36. One end of this spring 36 passes through a hole in the extreme right end of sleeve 35 and terminates there with a bend as shown in Figure 13 sufficient to prevent the spring from being pulled out through the hole. The other end of spring 36 terminates in a hole 37 in motor mounting plate 3 with a bend sufficient to prevent the end of the spring from being pulled out of the hole. The spring is wound in such a direction as to cause shaft 9 to tend at all times to rotate in a clockwise direction when viewed from the right side of the timer. Securely united to sleeve 35 by screw 38 or other suitable means (see Fig. 2), is driving ring 39. Also, securely fastened by a press fit or shrinkage to sleeve 35 is pinion 40. Free to rotate on sleeve 35 within limits as will be hereinafter explained, are a series of intermediate driving rings 41 and a tripping ring 42, all of which must be assembled on sleeve 35 before pinion 40 is pressed or shrunk on. For convenience, these driving rings may be called cams, as they have an intermittent action, although that term may not be technically accurate. Tripping ring or cam 42 is free to rotate through only a small arc limited in one direction by the tip of screw 43 and in the other by detent or catch 44.2 as best illustrated in Figure 4.

It will be noted that driving cam 39 has united thereto an extension or short bar 45 at the top thereof (Fig. 2). This bar 45 extends to the right sufficiently when cam 39 revolves, to collide with and engage a similar extension or bar 46 on the adjacent intermediate ring 41, but not sufficiently to contact the second intermediate ring to the right. The result of this arrangement is that driving ring 39 is free to rotate without driving its adjacent cam 41 until its extension 45 collides with extension 46 of the adjacent ring and any further rotation of driving ring 39 in the same direction will compel the next adjacent ring to rotate with driving ring 39. Similarly, the projection 46 of any one of the intermediate cams 41 will engage the projection on the next adjacent ring to its right and cause the adjacent ring to revolve. The projection 46 of intermediate ring 41 at the extreme right end of the series will, if rotated sufficiently far, collide with projection 47 on tripping ring 42 and further rotation will cause ring 42 to rotate within fixed limits.

From the foregoing, it will be apparent that driving ring 39 can rotate several turns from one

extreme rotative position to the opposite extreme before the engagement of the projections on the various cams with the projections on their respective adjacent cams will finally transmit motion of driving cam or ring 39 to tripping ring 42. Assuming that each projection occupies $1/40$ of the periphery of its ring, each ring would be free to rotate a maximum amount of $38/40$ of one complete revolution from one extreme rotative position where one side of its projection strikes one side of the projection on the adjacent cam or ring to the opposite extreme position where the other side of its projection strikes the other side of the projection on the adjacent ring and any additional rotation of the first ring will thereafter compel the adjacent cam to rotate with it. Thus a series of such cams consisting of one driving cam, one tripping cam, and ten intermediate cams would, if the cams of the series at the start were positioned in one extreme position, permit driving cam 39 to rotate $11 \times (1 - 2/40)$ or 10.45 turns before all slack in the series would be taken up and tripping cam 42 forced to rotate.

The cam or driving ring assembly just described is one of the novel features of this invention. For a given time interval between the starting of the timer and the forced rotation of tripping cam 42, shaft 9 may rotate as much as ten times as fast with the series of cams interposed between shaft 9 and cam 42 as if shaft 9 were coupled directly to cam 42. Depending upon how little or how much slack exists in the series of rings when in set position, that is, at the start of rotation, driving ring 39 may have to rotate any amount between zero turns and 10.45 turns before tripping ring 42 will be forced to rotate and to accomplish its purpose as hereinafter explained. Rotation of tripping ring 42 starts a succession of events which brings the timing period to an end. It is essential, for the highest degree of accuracy of the timer, that rotation of ring 42, when it once commences, shall proceed relatively fast. If ring 42 were to turn only one tenth as fast as is provided for by this invention, then the magnitude of the errors in timing that could result from imperfections in the shaping or fitting of various parts of the timer or from vibration or impact during the final interval while ring 42 was rotating would be materially increased. Likewise, any time elapsing between the instant when the surfaces of clutch members 17 and 18 come together and the instant when the steep sides of their respective teeth come into engagement to provide positive driving action would cause approximately ten times as great an error in the duration of the interval which the timer would provide if shaft 9 were coupled directly to tripping cam 42 as when a series of ten intermediate rings is employed. The operation of such a series of cams as just described is far less subject to interference from dust, grit, dried lubricants, etc., than is that of the relatively tight fitting threaded device employed in many timers at present wherein an internally threaded member must travel along the threads of an externally threaded member a distance roughly equal to the circumference of the threaded member times the number of turns it makes in determining the time interval.

As previously stated, spring 36 is wound and so arranged at its ends as to tend to rotate shaft 9 in a clockwise direction when viewed from the right side of the timer. The number of turns against the torque exerted by spring 36 which shaft 9 must make from any given starting position, and consequently the amount of time during

which shaft 9 must turn after it starts into motion before tripping cam 42 will be forced to turn, will depend upon how far spring 36 is permitted to rotate shaft 9 in a clockwise direction to reach a stopping position. In other words, the amount of slack that is arranged for in the assembly of rings above described at the time shaft 9 commences to rotate will determine the interval of time between the start of rotation of shaft 9 and the forced rotation of tripping ring 42. To stop the spring-driven clockwise rotation of shaft 9 at selected positions corresponding to definite time markings on an indicating dial, pinion 40 drives gear 48 through the center of which sleeve 49 extends, the gear and sleeve 49 being rigidly united by press fit, key, or pin. Sleeve 49 and consequently gear 48 are rigidly fastened to shaft 50 by set screw 51 (Fig. 18). Shaft 50 is supported for rotation at its right end by bearing 52 which is pressed into side plate 1 and at its left end by bearing 53 formed in axle 54, which axle may be united rigidly to motor mounting plate 3 by screw 55 or other suitable means (Fig. 18). Supported for rotation as a unit about axle member 54 are sleeve 56 and crown gear 57 rigidly united by press fit or otherwise.

Between sleeve 49 and sleeve 56, a plurality of identical cams or rings 58 are installed on shaft 50 on which they are free to rotate within certain limits. Each of these rings is similar in construction to ring 41 shown in Figures 14 and 15, having a projection or finger 59 (Fig. 2) which corresponds in design and purpose to projection or finger 46 on cam or ring 41. Sleeve 49 also has a projection 60 which extends outward from shaft 50 so far that projection 59 of cam or ring 58 adjacent to sleeve 49, if rotated, will eventually strike projection 60 and either be held against further rotation or will force sleeve 49 and gear 48 to rotate with ring 58. Sleeve 56 has a projection 61 (Fig. 2) which extends over the rim of its adjacent cam or ring 58 far enough so that projection 59 of adjacent ring 58 cannot pass projection 61 and yet projection 61 does not extend far enough to engage projection 59 of the second cam to the right of sleeve 56. From the earlier description of the functioning of the series of cams or rings carried by shaft 9 it will be apparent that an assembly consisting of sleeve 56, four intermediate cams 58 and sleeve 49 all installed on a single shaft 50 will permit a corresponding number of rotations of sleeve 49 from one extreme rotative position where one side of the projection of each element in the assembly engages one side of the projection of its adjacent element to the other extreme rotative position where the other side of the projection of each element engages the other side of the projection of its adjacent element. In the case of a series of elements consisting of sleeve 56, four cams or rings 58, and one sleeve 49 the projections on each of which span $\frac{1}{40}$ of the periphery, sleeve 49 and consequently gear 48 are free to rotate $5 \times (1 - \frac{1}{40}) = 4.75$ turns from one extreme position to the other, where further rotation of sleeve 49 would be impossible unless sleeve 56 were rotated with sleeve 49. The number of turns pinion 40 can rotate under such conditions before the maximum possible slack in the series of cams or rings on shaft 50 will be eliminated depends upon the ratio of the number of teeth in gear 48 to the number in pinion 40. For example, if gear 48 has $2\frac{1}{2}$ times as many teeth as pinion 40, then pinion 40 is free to rotate $2\frac{1}{2} \times 4.75$ or 11.875 turns.

As explained above, spring 36 exerts a torque

on pinion 40 urging said pinion clockwise when viewed from the right side of the timer. Pinion 40 then tends to cause gear 48 to rotate in a counterclockwise direction. Obviously, spring 36 by this means, if sleeve 56 is held against rotation, can rotate pinion 40 only until all slack between sleeve 49, cams 58, and sleeve 56 has been taken up. So, if motor 8 has been driving shaft 9 for a predetermined period of time at the end of which tripping ring cam 42 has been forced to rotate enough degrees to accomplish a function to be later explained, then, when clutch members 17 and 18 disengage, spring 36 will act to reset shaft 9 to the desired starting reset position determined solely by the rotative position in which sleeve 56 may have been placed. The number of turns the motor must make and consequently the time interval that must expire while shaft 9 is rotating from its starting or reset position to a rotative position where tripping cam 42 will accomplish its tripping action is adjustable and can be fixed by merely rotating sleeve 56 on pivot member 54. With a ratio of $2\frac{1}{2}$ to one between the number of teeth on gear 48 and the number on pinion 40, and with sufficient slack in the assembly on shaft 50 to permit gear 48 to rotate in excess of 4 turns from a reset position before collision of the projections on the elements of the assembly with each other can arrest rotation of gear 48, it is possible to adjust sleeve 56 to any rotative position permitting shaft 9 to rotate from a minimum of zero turns to a maximum of at least ten turns before tripping ring or cam 42 is forced to turn.

To rotate sleeve 56 and to fix it in set or reset position (Figs. 2, 4 and 21), pinion 62 is united to a dial shaft 63 in driving engagement with crown gear 57. Shaft 63 passes through and is united to a collar 64 which in turn is mounted for rotation in a bore through the approximate center of front plate 5, and its inner end is supported for rotation by bearing bore 70 in motor mounting plate 3 (Fig. 6). Pinned to collar 64 on the inner side of front plate 5 is gear 65. On the outer side of collar 64 are pinned minutes indicator arm 66 and washer 67. Collar 64 acts as a bearing for dial shaft 63 and also serves to transmit rotation of gear 65 to minutes indicator arm 66. The position of minutes indicator arm 66 is clearly indicated by the 20 minutes scale 68 on the face of dial 69. Dial 69 is enclosed within a cover 71 having transparent material 72 covering a circular hole in the cover through which the dial may be observed. The cover and transparent material are clamped to front plate 5 by screws 73. The transparent material may be cemented or riveted to the inner surface of cover 71 to hold it securely to said surface.

On the outer end of shaft 63 is installed sleeve 74 at the inner end of which and integral therewith is cup disk 75 having saw teeth cut into its rim. These teeth normally engage a flat side of pin 76 extending from front plate 5 and by this engagement cup disk 75 is prevented from rotating in a clockwise direction when viewed from the front of the timer. The effect of spring 36 acting through pinion 40, gear 48, and the assembly of rings on shaft 50 traced to crown gear 57, will be that spring 36 tends to rotate crown gear 57 in a counter clockwise direction when viewed from the right side. To resist such rotation of crown gear 57, dial shaft 63 which carries pinion 62 must be held against rotation in a clockwise direction. Accordingly, the saw teeth of cup disk 75 are cut so that when cup disk 75 is urged to rotate in a clockwise direction the

surfaces of its teeth which lie in the plane of shaft 63 are forced against a surface of pin 76 which lies in substantially the same plane, and cup disk 75 and consequently shaft 63 are prevented from rotating. When it is desired to rotate shaft 63 for the purpose of adjusting the interval for which the timer is set, cup disk 75 is readily brought out of engagement with pin 76 by merely pulling forward knob 77 which is securely fastened to shaft 63 by set screw 78. Pulling out on knob 77 and shaft 63 compresses spring 79 but when the knob is released cup disk 75 is automatically forced back into engagement with pin 76 and held against rotation in a clockwise direction thereby. It is held against rotation in the opposite direction by a torque exerted by spring 36.

Pinned directly to the outer surface of cup disk 75 is seconds indicator arm 80, the position of which is indicated by the markings on seconds scale 81 which is divided into 60 equal divisions representing seconds. In one preferred form of this invention, main shaft 9 is geared to motor 8 so that shaft 9 turns at the rate of one half revolution per minute and, if the numbers of teeth on gears 40 and 48 are 20 and 50 respectively, then $\frac{1}{2}$ of $\frac{2}{50}$ or $\frac{1}{50}$ of a turn of crown gear 57 will change by 60 seconds the interval between the time of starting of the timer into operation and the time when tripping cam 42 will be forced to rotate. Therefore, if the number of teeth in crown gear 57 is 55 and the number in pinion 62 is 11, one full turn of shaft 63 will rotate crown gear 57 one fifth of a turn and will change by 60 seconds the interval for which the timer is set. Correspondingly, one sixtieth of a turn of shaft 63 will vary the time interval by one second. Scale 81 which indicates the position of dial indicator arm 80 is divided into 60 divisions, so each division will correspond to one second change in setting of the time interval. If cup disk 75 has 60 teeth, then dial indicator arm 80 may be automatically locked at any of the one second divisions of scale 81.

To indicate the number of minutes in the interval for which the timer is set, pinion 62 is made sufficiently long to engage gear 82 which is mounted for rotation on pivot stud or screw 83 which in turn is fastened securely into front plate 5. Rigidly fastened to gear 82 and concentric thereto for rotation on pivot 83 is pinion 84 which engages gear 65. Consequently, rotation of pinion 62 with shaft 63 through any arc will cause minutes indicator arm 66 to rotate through an arc determined by the ratio of the gearing just described between pinion 62 and gear 65. If this ratio is 25:1 for example, 20 full turns of knob 77 and seconds indicator arm 80 will cause minutes indicator arm 66 to turn $\frac{2}{25}$ of one turn. Therefore, if scale 68 is constructed to cover $\frac{2}{25}$ of 360 degrees and is divided into 20 equal divisions, the movement of minutes indicator arm 66 from one division to another will correspond to a one minute change in the interval for which the timer is set. Accordingly, the dial mechanism as just described will indicate the number of whole minutes of timing interval by the position of minutes indicator arm 66 relative to scale 68 and the number of additional seconds by the position of seconds indicator arm 80 relative to seconds scale 81.

An important advantage of this dial mechanism over other indicating mechanisms of timers possessing flexibility and accuracy more or less similar to that of my invention is the means

whereby the dial mechanism automatically locks itself in whatever adjusted position it may have been manually placed by an operator.

The means provided to control and adjust the time interval between the starting of the motor and the tripping by cam 42 has been explained. The effect of rotating tripping cam 42 will now be explained. A bell crank lever having arms 44 and 44.1 is mounted on pivot pin 86 upon the side plate 1 and held by nut 87. The arm 44 has a detent catch united to the lower end thereof and the arm 44.1 is urged downward by a tension spring 85. Projection 47 of cam 42 is of such length and so positioned that when it rotates in a counterclockwise direction as viewed from the right side of the timer it will strike the detent catch 44.2 and carry it backward against the tension of spring 85. A detent arm 88 is united to collar 89 and rigidly secured to shaft 90 at the right side of the timer by set screw 91 in collar 89 (Fig. 22). United to collar 92 is a tripping bar supporting arm 93 which is rigidly united to shaft 90 by set screw 94. Pinned to detent arm 88 at the right and pinned to tripping bar supporting arm 93 at the left is tripping bar 95. Shaft 90 is pivoted in a bearing at its right end in right side plate 1 and in a bearing at its left end in left side plate 2. Detent arm 88, tripping bar arm 93, tripping bar 95, and shaft 90 are constructed to partially revolve as a unit through a small arc with the axis of shaft 90 as a center. Suitable spacer collars on shaft 90 prevent lateral motion of said shaft.

In tripping bar 95 there are five threaded holes number 96 (Fig. 22). These holes are provided to accommodate, in any desirable combination for purposes which will later be explained, pins threaded at their lower ends of the type numbered 97 shown in Figures 2, 3 and 4. In detent arm 88 there are two threaded holes 98 and 99, either one of which, depending upon the performance desired of the timer as will hereinafter be clarified, will accommodate a screw 100 as shown in Figures 3 and 4.

A panel 101 made of insulating material is mounted at the lower front of the housing and has passing through it a plurality of screw terminals 102 with nuts 103 as shown in Figures 1, 3 and 4. Panel 101 may be secured to lips 104 extending from side plates 1 and 2 by screws 105 or other suitable means. Flexible wires 106 (Figs. 3 and 4), lead from terminals 102 to contact members 107, 108, 109, 110 and 111 and are united to said members by screws 112. Contact members 107, 108, 109, 110 and 111 all are tipped with silver tips 113 or other metal of high conductivity and are united to insulating supporting members or bars 114 by screws 112 and 115 which pass through the insulating members and screw into threaded bores in plates 116. Insulating members or bars 114 are pivoted freely on shaft 117 which is supported at its right end by side plate 1 and at its left end by side plate 2. Spacer sleeve 118 and set screw 119 together with other spacer sleeves 118.1 on shaft 117 serve to prevent sideways motion of the insulating members and of shaft 117. Wires 106 pass freely through bores 120 in insulating members 114 (Fig. 5). Tension springs 121 have their upper ends hooked to insulating members 114 and their lower ends to brackets 122 extending outward from and united to back plate 6 and act to rotate insulating members 114 a few degrees about shaft 117 in a clockwise direction when viewed from the right side of the timer.

In order that insulating members 114 may be held in various angular positions about shaft 117, the purposes of which will be clear from explanations hereinafter provided, a retaining strip 120 containing threaded bores 124 is riveted or united to back plate 8 as shown in Figures 3, 4 and 5 and in greater detail in Figures 25 and 26, and screws 125 are inserted in the threaded bores as necessary to hold insulating members in the required positions. For example, with insulating members positioned as in Figures 1 and 2, screws are required in bores A and B (Fig. 26) to support against the pull of springs 121 the rear ends of insulating members 114 carrying contacts 107 and 108. If desired that contacts 107 and 108 be normally closed, instead of normally open as shown in Figures 1 and 2, then the screw in bore A could be removed and spring 121 could force contact 108 into engagement with contact 107. Similarly, with contacts 109, 110 and 111 in the positions shown in Figures 1 and 2, screws are required in bores C and E (Figs 26), but none is required in bore D because it is desired that spring 121 be allowed to hold contact 110 against contact 111. If desired that contacts 110 and 111 as well as contacts 109 and 110 be normally open, screws could be inserted in bores E, F, and G instead of in bores C and E. Experience has proved that various different relationships of contacts in the non-operating condition of the timer may be found necessary to meet the needs of the various uses made of a timer of this type and accordingly screws may be inserted in bores 124 in the required combinations or additional bores may easily be provided if found desirable.

At the left end of actuating plate 126 and united to or integral with it, shaft 34 (Figs. 27 and 28) is pivoted in left side plate 2. Also at this end is a clutch operating arm 28 in which there is bore 127 for attaching one end of a tension spring. At the right end of actuating plate 126 and also united to or integral with it is shaft 128 which is pivoted in right side plate 1. Figures 27 and 28 show the actuating plate 126 with a clutch operating arm 28 assembled to shaft 34, and also show a plunger lever arm 129 and a short arm 130, which is riveted to sleeve 131, assembled to shaft 128. Sleeve 132 serves as a spacer to prevent sideways motion of the assembly shown in Figures 27 and 28 between side plates 1 and 2 and as a convenient anchorage for one end of a tension spring 133. Set screw 134 fastens plunger lever arm 129 rigidly to shaft 128 and set screw 135 fastens arm 130 rigidly to shaft 128 (Fig. 5).

A solenoid 145 of conventional type is securely fastened to right side plate 1 by studs 137, nuts 138, and screws 139. A plunger 140 for the solenoid is movable upward by the force of spring 141 acting through clutch operating arm 28, shaft 34, actuating plate 126, shaft 128, plunger lever arm 129, pin 142, connecting link 143, and pin 144. Plunger 140 is movable downward by the magnetic attraction of solenoid coil when suitable electric power is applied to the terminals of said coil. Wires 146 connect the solenoid coil with terminal screws 102 on panel 101.

The power exerted by the solenoid coil may be augmented by surrounding the coil by a laminated series of iron plates secured by non-magnetic frames 136 and bolts 137.

Whenever plunger 140 moves downward, actuating plate 126 is tilted counter clockwise when viewed from the right of the timer. A screw 147, with head of suitable height is driven into

the bore at K in actuating plate 126, as shown in Figures 27 and 28, and when plate 126 is tilted counter clockwise, will strike the insulating member 114 on which contact 107 is mounted and will bring contacts 107 and 108 together so that current can flow from one to the other. Contacts 107 and 108 may be so connected to a source of electric power that their closing, one upon the other, will close a circuit to the coil of solenoid 145 through wires 146, and downward motion of plunger 140 will then cause the circuit to the coil to be closed and plunger 140 held by magnetic force in the down position until the connection to the source of power is broken, either by the separation of contacts 107 and 108 or by a manually operable switch, or otherwise as desired. Or, the leads 148 to motor 8 may also be connected through terminals 102 so that the closure of contacts 107 and 108 serves to conduct power to the motor, and the downward motion of plunger 140 will not only serve to lock itself down by the action described above, but will likewise start and keep motor 8 running until the contacts open or until the connection to the source of power is otherwise broken. Furthermore, since clutch operating arm 28 rotates with actuating plate 126 as a unit, downward motion of plunger 140 will cause clutch member 17 to engage member 18 and rotation of motor 8 will cause shaft 9 to rotate.

Similarly to the action of screw 147 is forcing contact 107 against contact 108, other screws may be driven into the other bores in actuating plate 126 and cause contacts 109, 110 and 111 to engage or disengage each other as may be needed for various timing processes. For example, a screw 147 of suitable height driven into bore L of plate 126 will, when actuating plate 126 is tilted counter clockwise by the action of solenoid 145, cause contact 110 to break connection with contact 111 and to make connection with contact 109 and that will continue to be the condition of the contacts until solenoid 145 allows plunger 140 to rise under the action of spring 141 thereby tilting plate 126 back to its normal horizontal position or until a pin 37 carried by tripping bar 95 moves upward, and by raising the tail of an insulating member 114, causes a change in the positioning of the contacts. That the use of one or more contact screws 147 in other bores of plate 126 may serve to provide different action of the contacts will be plain to anyone acquainted with electrical control devices and accordingly need not be explained further. It should be noted, however, that if contact screws 147 are mounted in bores M and N in the forward side of actuating plate 126, the upward movement of plunger 140, instead of its downward movement, and the resultant clockwise tilting of actuating plate 126 may be employed to close circuits through the contacts as above explained. The cycle of operation of the timer may be started by either closing a circuit to solenoid 145 or by opening the circuit, depending upon selected changes in the arrangement of the timer parts.

With the timer parts assembled as shown in Figure 4, downward motion of plunger 140 will cause short arm 130 to rotate counter clockwise with actuating plate 126 as a unit. Such rotation will raise arm 130 from its position as shown in Figure 4 so that a considerable space will exist between it and the tip of screw 106 which is screwed into bore 98 of detent lever arm 99 and, for security, may be locked in place by a lock-nut on the under side of the detent lever arm.

Prior to such rotation of arm 130, the pressure exerted against screw 100 by it, which may be traced to the action of spring 141, serves to overcome the tension spring 133 and to cause the forward point of detent arm 88 to be raised slightly above the point of detent 44.2 as shown in Figures 3 and 4. As soon as the short arm 130 is rotated counter clockwise, the forward point of detent lever arm 88 will be held by the detent 44.2 against counter clockwise rotation, and clockwise rotation of detent 44.2 as viewed from the right side of the timer, will serve to release the forward point of detent lever 88 and to allow spring 133 to rotate detent lever arm 88 and tripping bar 95 in a counter clockwise direction. The required clockwise rotation of detent 44.2 will be forced by the action of projection 47 of tripping cam 42 at the end of the interval for which the timer has been set. The counter clockwise rotation of tripping bar 95 about the bearings of shaft 90 as a center will serve to raise screws 97 in bar 95 and cause them to strike insulating members 114 and to rotate said members a few degrees about shaft 117 as a center. The consequent rotation of the contacts may be employed either to force one contact against another to close a circuit or to draw one contact away from another to open a circuit, as may be required to utilize the timer in the accomplishment of a given function. For example, if plunger 140 has been locked in a down position by electric current passing through contacts 107 and 108, then the release of detent lever arm 88 by detent 44.2 and the resultant pressure of screw 97 against the insulating member 114 which carries contact 108 will force contact 108 to separate from contact 107, the circuit to solenoid 145 and motor 8 will be broken, and plunger 140 will then rise under the action of spring 141 to its non-operating position ready for another cycle of operation. At the same time arm 130 will force screw 100 and tripping bar 95 to rotate in a clockwise direction as viewed from the right side of the timer until the forward point of detent lever arm 88 has risen slightly above the point of detent 44.2 to permit spring 35 to rotate bell crank arm 44 counter clockwise until detent 44.2 is beneath the point of detent lever arm 88. Since, as already explained, the rotation of clutch lever arm 28 in a counter clockwise direction, as viewed from the left of the timer, will cause push rod 27 to rotate clutch release lever 25 and thereby separate clutch member 17 from member 18, the upward motion of plunger 140 following the opening of the circuit through contacts 107 and 108 will open the clutch and disconnect motor 8 from main shaft 9 and allow spring 36 to reset said shaft to its starting position.

In practice, needs arise for the accomplishment of numerous different operations by timers of this class. It is for that reason that bores 99, one for each contact, have been provided for screws 97 in tripping bar 95; that one bore for screws 147 for each contact has been provided on each side of actuating plate 126; and that a terminal screw 102 has been provided for the wire to each contact member and for each wire leading from motor 8 and solenoid 145. In addition, two bores, one above the other, are provided in the lower end of connecting link 143 so that plunger 140, when connected to link 143 with pin 144 in the lower of the two bores instead of in the upper one as illustrated, may in its normal non-operating condition be held in a downward

position by electric current and allowed to rise to an operative condition by the action of spring 141 upon the breaking of the electric circuit. With the plunger so connected, upward motion 5 of the plunger must be utilized to cause arm 130 to draw away from screw 100 instead of pushing against it, so as to permit detent lever arm 88 to rotate counter clockwise when viewed from the right side of the timer when released by detent 44.2. To provide for such a condition, screw 100 may be shifted to bore 99 in detent arm 88 and, by loosening set screw 135, arm 130 may be rotated 180 degrees so as to extend forward instead of backward from shaft 128. Also, in order that clutch members 17 and 18 may be brought into engagement by upward motion of plunger 140 instead of by downward motion of said plunger, push rod 27 may be connected between pin 149 on clutch operating arm and clutch operating lever 25 as shown in Figure 12 instead of between pin 29 and clutch operating lever 25 as shown in Figure 3. In order that motor 8 may operate when plunger 140 is in the raised position, screw 147 in actuating plate may be shifted from bore K to bore M.

Figure 30 shows a diagram of the circuits of the timer connected in one of the several possible ways. Leads marked P have voltage impressed upon them from any suitable source. Momentary pressure on push button B will cause plunger 140 of solenoid 145 to be pulled downward by the action of the solenoid coil whereupon contact 107 by action of screw 147 will close against contact 108, thereby electrically locking plunger 140 in the down position and at the same time applying power to motor 8 causing it to drive the timer mechanism. Also power which has been applied to lead L1 through contacts 110 and 111 will be disconnected by the action of another screw 147 in bore L forcing contact 110 away from contact 111 and power will be applied to lead L2 through contacts 109 and 110 by the movement of contact 110 into engagement with contact 109. Motor 8 will accordingly drive the time mechanism with all contacts in the condition just described until the expiration of the time interval indicated by dial indicator arms 86 and 89. At the end of said interval, contacts 107 and 108 will open by pressure of screw 97 against the insulating member 114 which carries contact 108 and will allow plunger 140 to be pulled upward by spring 141, stopping motor 8, and restoring contacts 109, 110 and 111 to the condition illustrated in Figure 30.

In a characteristic operation of my timer, the timer is assembled in starting position with the "secondary" rings in their extreme released position. That is, they are gathered together by the action of the spring 36 as far as possible by the spring action, the limit being fixed by detent or lug 61 on sleeve 56, and a predetermined amount of slack is left in the primary rings.

The knob 77 is then turned manually to set the seconds and minutes hands at the points on 65 the dial indicating the desired time selected to have elapsed from the starting of the motor until the current is cut off therefrom.

As the knob is turned, the "primary" and "secondary" rings are successively rotated out of their 70 starting or released positions by the action of the gears 62-57 and are set or spaced to positions corresponding to the points indicated by the hands on the dial which indicate the time required for the motor to drive the primary and secondary rings to the end of the travel neces-

sary to cause them to actuate the tripping mechanism and throw the switches which will cut out the motor and also cause the desired changes in the current running the machine or process to which the timer is attached or connected. At the same time, gears 62—82—84—65 will set the minutes hand the shaft 63 and sleeve 74 will set the seconds hand at the desired points on the dial. The starting button is then pushed and the motor started which will run until stopped by a switch as heretofore described.

When the motor stops and the clutch releases, the spring 36 carries the driving rings back to their predetermined set or starting position where the rings 58 have been carried back as far as 15 permitted by lug or finger 61 on sleeve 56. The cycle can then be repeated by pushing the starting button manually or by arranging means connected with the machine to which the timer is attached to push the starter button.

When my machine is assembled, all of the driving rings are put in so-called chock-a-block position, that is, all of them are turned until each of the fingers is in contact with the rear of the finger on the preceding ring, and I refer to this position as the "assembled" position.

When the knob is used manually to withdraw the detent 61 from the finger on the adjoining driving ring, the action of the spring 36 will cause the driving rings to follow until all of the fingers of the rings 58 are in contact either with the detent 61 or with the finger on the next preceding driving ring, and I refer to this position as the "set" or "reset" position. In this position, the dog 76 bearing against the teeth of the crown or cup disk 75 will prevent any farther rearward movement of the sleeve 56 and the detent 61 thereon. But when the driving effect of the motor has forced all of the fingers on the driving rings into contact with their next preceding ring, the position may be called the "tripping" or "final" position and as soon as the rings reach this position, the switch is tripped, thus throwing out the clutch, stopping the motor, and allowing the restoring spring 36 to reassemble the rings in their set or reset position.

Many modifications in the form and arrangement of parts may be made and such may be applied to the control of electric circuits in many ways other than those specifically mentioned here without departing from the spirit of my invention and I do not limit my claims to the particular forms shown in the drawings. Many circuits and sequences of contact operation for timing devices have been devised to meet the needs in that field, but they constitute no part of my invention and need not be explained here.

I claim:

1. A timer of the class described comprising a housing, an electric motor, a clutch shaft rotatably mounted in the housing, a motor shaft operatively connected to the clutch shaft by gearing, a clutch having one member mounted upon a sleeve rigidly united to the clutch shaft, and its coacting member united to a sleeve slidable lengthwise upon said shaft and rotatable on the shaft, a fixed driving ring as described rigidly united to a second sleeve united to the shaft and spaced apart from the clutch sleeve, a primary series of successively coacting intermediate driving rings rotatably mounted upon the second sleeve and arranged to actuate a tripping ring at the end of their limits of travel in one direction having linkage to throw a switch arranged to

cut off the current from the motor after a predetermined period of operation of the motor.

2. A timer as set out in claim 1, and a manually operable knob and shaft mounted in the housing with intermediate gearing operatively connecting the knob shaft to the second sleeve on the clutch shaft whereby the driving rings may be manually set in various positions of adjustment by the knob.

3. A timer as set out in claim 1, and a manually operable knob and knob shaft mounted in the housing with intermediate gearing connecting it to the second sleeve on the clutch shaft whereby the driving rings may be manually set in various positions of adjustment, a graduated dial mounted upon the housing adjacent the knob and a hand united to the knob shaft to indicate on the dial the time required for the motor to operate a sufficient time to drive the driving rings far enough to actuate the tripping mechanism.

4. A timer as set out in claim 1, a manually operable knob and knob shaft mounted in the housing with gearing operatively connecting the knob shaft to the second sleeve on the clutch shaft whereby the driving rings may be manually set in various positions of adjustment by the knob, a graduated dial mounted upon the housing, and minute and second hands arranged to be set by the knob to indicate given periods of time in minutes and seconds.

5. A timer as set out in claim 1, a manually operable knob and knob shaft mounted in the housing with gearing operatively connecting the knob shaft to the second sleeve on the clutch shaft whereby the driving rings may be manually set in various positions of adjustment by the knob, a graduated dial mounted upon the housing, and minute and second hands arranged to be set by the knob to indicate given periods of time in minutes and seconds, the seconds hand being united to a sleeve fixed to the knob shaft, and the minutes hand being carried by a sleeve geared to the knob shaft by reduction gearing.

6. A timer of the class described, comprising 45 a housing, an electric motor, a clutch shaft rotatably mounted in the housing, the motor shaft being operatively connected to the clutch shaft by reduction gearing, a clutch having one member mounted upon a sleeve rigidly united to the clutch shaft, and its coacting member united to a sleeve slidable lengthwise upon said shaft and rotatable on the shaft, a fixed driving ring rigidly united to a second sleeve united to the shaft and spaced apart from the clutch sleeve, a primary series 50 of successively coacting intermediate driving rings rotatably mounted upon the second sleeve arranged to actuate a tripping ring at the end of their limits of travel in one direction, a solenoid mounted in the housing and having a movable core, an electric circuit to supply current to the solenoid and to the motor, adjustable switches to cut in or cut out the current to or from either the motor or the solenoid, a lever pivoted in the housing having one end pivoted to the core of the 55 solenoid and its opposite end operatively connected to one end of a spring arranged to urge the movable core out of the solenoid coil, and a spring-held switch-actuating lever mounted in the housing having one end united to a tiltable switch plate carrying one or more pusher studs and its opposite end arranged to be engaged by a detent formed integral with one arm of a bell crank lever pivoted in the housing the opposite 60 end of which is spring-held in set position, the 65 tripping ring having an arm projecting there- 70 75

from arranged to contact and carry the detent out of contact with the switch-actuating lever and allowing the switch-actuating lever to rock on its pivot and to tilt the switch plate as necessary to open or close the circuit to the motor or the solenoid.

7. A timer as described in claim 6, and a coiled compression spring mounted upon the clutch sleeve arranged to urge the slideable clutch member along the sleeve and into engagement with the fixed clutch member.

8. A timer as described in claim 1, and a secondary shaft parallel to the clutch shaft and having its outer end journaled in a side plate of the housing and its inner end enlarged and journaled in a tubular bearing mounted in a supporting plate united to the housing, said secondary shaft being geared to the clutch shaft and having rigidly united thereto a sleeve with a projecting detent, and a sleeve rotatably mounted on said bearing with a lug or finger projecting laterally therefrom arranged to contact a similar lug or finger formed on the periphery of the first of a secondary series of successively coacting driving rings or cams rotatably mounted on the secondary shaft between said bearing and the fixed sleeve.

9. A timer of the class described, comprising a housing, a motor, a clutch shaft rotably mounted in the housing, the motor shaft being operatively connected to the clutch shaft by reduction gearing, a clutch having one member mounted upon a sleeve rigidly united to the clutch shaft, and its coacting member united to a sleeve slideable lengthwise upon said shaft and rotatable on the shaft, a fixed driving ring rigidly united to a second sleeve united to the shaft and spaced apart from the clutch sleeve, a primary series of successively coacting intermediate driving rings rotatably mounted upon the second sleeve arranged to actuate at the end of their limits of travel in one direction a tripping ring with linkage arranged to cause said tripping ring to throw a switch to cut off the current from the motor after a predetermined period of operation of the motor, a secondary shaft having one end mounted in the housing and its opposite end enlarged and journaled in a tubular bearing mounted in a supporting plate, said secondary shaft being geared to the clutch shaft and having rigidly united thereto a sleeve with a projecting detent, a sleeve rotatably mounted on said bearing with a lug or finger projecting laterally therefrom arranged to contact a similar lug or finger formed on the periphery of the first of a secondary series of driving rings or cams rotatably mounted on the secondary shaft between said bearing and the fixed sleeve, and a helical spring mounted upon the clutch shaft to urge the slideable clutch member along the sleeve and into engagement with the fixed driving ring and arranged to rotate said driving ring and through it the intermediate driving rings to return them into their starting or set position when the current is cut off from the motor.

10. A timer as described in claim 9, and a manually operable knob and knob shaft mounted in the housing with gearing connecting it to the movable sleeve on the clutch shaft whereby the driving rings may be manually set in various positions of adjustment, a graduated dial mounted upon the housing adjacent the knob and a hand united to the knob shaft to indicate on the dial the time required for the motor to operate a

sufficient time to cause the driving rings to actuate the tripping mechanism.

11. In a timing mechanism, the combination with a shaft, of series of successive co-axial, co-acting rings mounted thereon, each rotatable freely in one direction with relation to its next succeeding ring through a predetermined arc only and thereafter in driving engagement with such succeeding ring, a plurality of circuit controllers, an electric motor, magnetically actuated clutching means providing a substantial driving engagement between said motor, said shaft and the initial ring of said series, a helical torsion spring installed co-axial with said series of rings upon a common shaft and connected to the initial ring of the series arranged to restore said rings to a predetermined starting position upon disengagement of said clutch, an indicator manually movable in relation to a stationary scale providing at all times an indication corresponding to the adjustable starting position of said ring, electrical connections between a source of power and both said motor and said magnetically operated connection means through said circuit controller, means responsive to one of said rings at the opposite end of the series for actuating said circuit controller, and means for disengaging said magnetically operated connecting means upon actuation of said circuit controller.

12. In a timing mechanism, the combination with a plurality of adjacent successively coacting co-axial rings, each rotatable through a definite arc with respect to its successive adjacent ring and thereafter in driving engagement therewith, a circuit controller, a motor, a magnetically operated clutch providing driving engagement between said motor and one of said rings, a spring connected to said ring for restoration of said ring to an adjustable starting position upon disengagement of said magnetically operated connecting means, means responsive to another one of said rings for actuating said circuit controller, and means for disengaging said magnetically operated connecting means upon actuation of said circuit controller.

13. In timing mechanism, a housing, a plurality of pairs of circuit controllers, an electric motor, a restoring spring, a magnetically actuated clutch, means for winding said restoring spring, driven at a substantially uniform speed by said motor between a starting and actuating position through the connection provided by said clutch, means responsive to said driven means for altering the relationship of at least one of the pairs of circuit controllers upon the attainment of said actuating position by said driven means whereby to break said clutch connection and allow restoration of said driven means to said starting position by said restoring spring, adjusting means including a disk with a toothed periphery for changing the starting position of said driven means to vary the time of travel of said driven means between its starting and terminating positions, an indicator rigidly connected to said adjusting means and movable therewith in close relation to a stationary time units scale carried by the housing, a dog rigidly installed in the housing structure and positioned for normal holding engagement with a tooth of the disk, means for manually forcing the disk out of engagement with said dog, and automatic spring-actuated means for restoring holding engagement between said dog and disk upon release of manual force.

14. In a timer of the class described, the com-

combination with a housing, of a clutch shaft mounted therein, a fixed clutch member rigidly united to the clutch shaft, a movable clutch member united to a clutch sleeve secured upon and slideable along said clutch shaft, a spur gear wheel united to said sleeve and having a central bore journaled upon an axle-bearing upon which said sleeve member and gear revolve and in which the clutch shaft may rotate, said axle-bearing being supported by a supporting plate in said housing, a collar rotatably mounted upon said shaft in said bore and slidably united to said sleeve, a compression helical spring mounted upon the shaft arranged to exert pressure in opposite directions upon the axle-bearing and the sleeve whereby the movable clutch member may be urged toward and into engagement with the fixed clutch member, an outer sleeve rigidly mounted upon the clutch shaft spaced from the clutch sleeve, having a fixed driving ring at one end thereof and a tripping ring at the opposite end thereof, with a series of intermediate driving rings revolvably mounted on the sleeve between the fixed ring and the tripping ring, a helical spring mounted upon the clutch shaft arranged to tighten as the clutch shaft is driven by the motor and to unwind when the clutch is released, and having its opposite ends united to the supporting plate and the outer sleeve respectively, a second shaft parallel to the clutch shaft and having one end journaled in the housing and the other end journaled in a bearing-sleeve rigidly supported in the supporting plate, a sleeve with a crown gear united thereto revolvably mounted on the bearing-sleeve and carrying a finger or lug arranged to contact and

actuate a similar lug or finger on the first of a series of coaxial successively coacting rings on said shaft, a sleeve secured on said shaft and spaced from the sleeve-bearing carrying a spur gear arranged to mesh with a corresponding gear mounted upon the outer sleeve on the clutch shaft, a manually operable shaft with a gear thereon in mesh with said crown gear whereby the relative positions of the driving rings may be adjusted in various set positions, and a motor geared to the clutch shaft by suitable reduction gearing.

15. In a timer of the class described, the combination with a motor, of a cutout switch to cut off the current therefrom, switch operating mechanism, a tripping ring to actuate said mechanism, a clutch shaft carrying a fixed and a slideable clutch member, a plurality of adjustable co-axial successively coacting driving rings arranged to revolve around the clutch shaft and to be actuated by the slideable clutch member when driven by the motor for a predetermined interval to actuate the tripping ring.

16. A combination as described in claim 15, and manually operable means to adjust the relative position of the driving rings so as to vary the time interval necessary to actuate the switch.

HARRISON I. TURNER.
